Filed Apr. 21, 1961, Ser. No. 104,739

12 Claims. (Cl. 24—205.1)

This invention relates to separable fastener stringers, wherein the scoops are fixed to one surface only of the stringer tapes, producing what I term a one-sided fastener, wherein scoops of coupled stringers become invisible when viewing the fastener from the other surface of the coupled stringers.

More particularly, the invention deals with separable fasteners of the character described, wherein the scoops of the stringers are provided one with a hook member and the other with a socket conforming to at least part of the contour of the hook member.

Still more particularly, the invention deals with a fastener of the character described, wherein the scoops are formed in pairs on each stringer and, still further, wherein markings are provided on the scoops of one stringer different from other markings provided on the scoops of the other stringers, so as to distinguish one stringer from the other stringer in production assemblage of the stringers.

The novel features of the invention will be best understood from the following description, when taken together with the accompanying drawing, in which certain embodiments of the invention are disclosed and, in which, the separate parts are designated by suitable reference characters in each of the views and, in which:

FIG. 1 is a diagrammatic enlarged plan view of a small sectional portion of a pair of separable fastener stringers illustrating one adaptation of my invention.

FIG. 2 is a section on the line 2—2 of FIG. 1.

FIG. 3 is a view, similar to FIG. 1, showing another adaptation of my invention.

FIG. 4 is a section on the broken line 4—4 of FIG. 3.

FIG. 5 is a view, similar to FIGS. 1 and 3, showing another form of stringer construction.

FIG. 6 is a section on line 6—6 of FIG. 5; and

FIG. 7 is a section on the line 7—7 of FIG. 5.

Considering FIGS. 1 and 2 of the drawing, 10 and 11 represent two small portions of two stringer tapes making up a separable fastener. Each tape has an inner bead 12, 13 and an outer bead 14, 15, the term "outer" being used with respect to the abutting edge portions 16 and 17. For purposes of description, the part of the stringer tapes between 14, 16, 15 and 17 may be defined as shelf portions 18 and 19, respectively.

Suitably fixed to the beaded surfaces of the tapes 10 and 11 are pairs of scoops 20, 21 and, in considering the structure of FIG. 1, as well as the structure shown in FIGS. 3 and 5, if these scoops in the several views are formed as molded or die cast members, attachment to the surfaces of the stringer tapes and the beads is by virtue of the extension of the molded or cast material into the interstices of the braid which establishes positive anchorage of the scoops to the stringers. At this time, it is also pointed out where reference is made to pairs of scoops, as in FIGS. 1 and 3, it will be understood that, in molding or casting the scoops, they may be cast in

2

pairs or in multiples of pairs, depending upon the capacity of the machine employed in producing the fastener.

The pairs of scoops 20 may be said to comprise a male scoop 22 and a female scoop 23; whereas, the pair of scoops 21 have corresponding male and female scoops 24 and 25, respectively. The coupling end portion of the male scoops have what might be termed hook-shaped coupling members 26 and 27, respectively; whereas, the female scoops include sockets 28 and 29, respectively, for reception of the members 27, 26 in coupling the pairs of scoops of the two stringers. Inner surfaces of the members 26 and 27 are rounded, as seen at 30 and 31, to receive rounded or bulbous heads 32, 33 on the female parts 23, 25, respectively. The male parts 22 and 24 include wear shelves 34 and 35, over which the heads 32, 33 respectively pass, these shelves extending to the edges 16, 17 of the tapes and overlying the shelf portions 18 and 19, respectively. Corresponding wear shelves are provided in the recess or socket portions 28 and 29, as indicated at 36 and 37. Both of the wear shelves overlie the shelf edge portions of the tapes and part of the outer beads 14 and 15, as will clearly appear from a consideration of FIG. 2 of the drawing. At this time, it is also pointed out that portions of the members 26, 27 and heads 32, 33 overlie these outer beads.

It will be noted that the pair of scoops 22, 23 have, on the exposed surface of the mounting end portions thereof, rectangular recesses 38; whereas, the pairs of scoops 24, 25 have similar round recesses 29. The purpose of this is to definitely distinguish what may be termed a righthand stringer from a lefthand stringer to facilitate production assemblage of the stringers. It will also be noted that outer surfaces of the members 26, 27 and heads 32, 33 have relieved portions, as indicated at 40, for facilitating coupling and uncoupling of the scoops of the two stringers.

It will clearly appear from a consideration of FIG. 2 of the drawing that the rounded corner portions of the members 26, 27, 32, 33 facilitate movement of these portions over the wear shelves, FIG. 2 illustrating the member 27 in section and the head 32 in section.

In FIGS. 3 and 4 of the drawing, I have shown a modified arrangement of pairs of scoops 41, 42 arranged on stringer tapes 10', 11', similar to the tapes 10 and 11, 45 and having beads 12', 13', 14', 15', again, similar to the beads of the tapes 10 and 11.

The pairs of scoops 41 comprise scoops 43 and 44 having hook-shaped coupling members 45, 46 at the outer coupling end portions of the scoops. The pairs of scoops 42 comprise scoops 47 and 48 also having, at their coupling end portions, hook-shaped coupling members 49 and 50. The scoops 43, 44 have, inwardly of the members 45, 46, female sockets 51 and 52 and the scoops 47 and 48 have similar sockets 53 and 54, the latter receiving the members 45 and 46, respectively; whereas, the members 49 and 50 engage the sockets 51 and 52, as clearly illustrated in FIG. 3 of the drawing. It will be apparent that all of the coupling members conform generally to the contour of the sockets.

The coupling members and sockets defined are arranged at the outer exposed surface of the scoops and over wear shelves 55, 56 on the scoops 43, 44 and 57 and 58 on the scoops 47 and 48, these wear shelves being generally similar to the wear shelves employed in the fastener

stringer shown in FIGS. 1 and 2. The mounting end portion of all of the scoops have, as an extension to the female sockets, recesses 59, 60, 61 and 62 for free movement of the coupling members in the sockets in the operation of coupling and uncoupling the scoops of the stringers. It will also be apparent that the coupling members or heads extend into opposed stringers to a point overlying part of the outer beads 14', 15'.

At this time, it is pointed out that, in the diagrammatic illustrations of FIGS. 1, 3 and 5, no attempt has been made to accurately indicate the contour of the scoops in order to simplify the present illustration. It will appear, however, from a consideration of the sectional views that the walls of the scoops are tapered for free engagement of the parts and for simplifying formation thereof, particularly when the scoops are molded or die cast. Furthermore, the sectioning used in FIGS. 2, 4, 6 and 7 are not to be considered limitations of the type of material employed, but rather in illustrating one adaptation and use of the invention.

With the structure shown in FIGS. 3 and 4, it will appear that the pair of scoops 41 have their coupling members and female sockets facing each other; whereas, with the pairs of scoops 42, the coupling members and sockets are in opposed directions to each other to operatively engage the pairs of scoops 41. With this construction, it will be apparent that two distinct lefthand and righthand stringers are employed in producing a separable fastener and the contour of the respective pairs of scoops will be sufficient to distinguish one scoop from the other, thus obviating the necessity of utilizing identifications, as at 38 and 39 in FIGS. 1 and 2 of the drawing.

Turning now to FIGS. 5, 6 and 7, here is shown another form of fastener, generally similar to the structures shown in FIGS. 1 to 4 and, wherein, stringer tapes 63 and 64 are employed, each having a single bead 65, 66 and each of the scoops 67 on the stringer 63 are of identical construction and the scoops 68 on the stringer 64 are also of identical construction, but differing from the scoops 67. With this construction, the scoops 68 have at their coupling end portion hook-shaped coupling members 69 which operatively engage sockets 70 in the scoops 67, conforming generally to the contour of the members 69, as will clearly appear from a consideration of FIG. 5 of the drawing.

At each side of the sockets 70, the scoops 67 include wall portions 71 and 72, within and between which the members 69 seat. These wall portions 71 and 72, as well as the members 69, are the full depth of the scoops and the members 69 have, at their lower outer corners rounded portions, as noted at 73 in FIG. 6 of the drawing; whereas, each of the wall portions 71 and 72 have corresponding rounded portions, the rounded portion of 71 being indicated at 74 in FIG. 7 of the drawing. These rounded portions facilitate free movement of 69, 71 and 72 over the shelf portions 63', 64' of the tapes 63, 64, as will clearly appear from a consideration of FIGS. 6 and 7 of the drawing. Furthermore, the rounded portions 73, 74 are adapted to forcibly engage the beads 65 and 66 respectively in coupling the stringers together, as diagrammatically illustrated in FIGS. 6 and 7.

Considering FIG. 5 of the drawing, it will appear that the scoops 67 have extended or slightly bulged sides, as at 75, merely to compensate for the contour of the members 69 and provide the required strength to the wall portions 72 where they join the attaching portion of the scoops.

With all forms of construction shown, it is apparent from the sections, FIGS. 2, 4, 6 and 7, that adjacent edges of the tapes will abut when the stringers are coupled together, so that the scoops become invisible in viewing the stringers from the lower sides of the coupled stringers, as illustrated in said views on the drawing. These lower sides are usually the outer surfaces of the coupled stringers, so that scoops of the stringers are

invisible from the outer surface. However, in some uses of separable fasteners of this type and kind, this non-scooped surface of the stringers may be arranged adjacent the body or member, in conjunction with which the fastener is used. This would be particularly the case in body garments where it would be desirable to have the relatively smooth surface of the stringers bear upon the body of the wearer.

Having fully described my invention, what I claim as new and desire to secure by Letters Patent is:

1. A one-sided separable fastener comprising a pair of stringer tapes, each stringer having bead means projecting on one surface thereof, scoops fixed to said surface of the stringers, the scoop of one stringer having a projecting coupling end portion including a hook-shaped coupling member, scoops of a companion stringer having at its coupling end portion a socket generally conforming to the contour of and adapted to receive the hook-shaped coupling member of scoops on said first named stringer, the bead means of said stringers being disposed inwardly of adjacent edges of coupled stringers to form on the tapes of the stringers projecting shelves, over which the coupling end portions of the scoops of both stringers overlie when said stringers are coupled together, and the coupling end portions of the scoops of both stringers also overlie part of the bead means on opposed stringers.

2. A one-sided separable fastener as defined in claim 1, wherein the coupling end portions of the scoops of both stringers include wear shelves overlying adjacent edge portions of the tapes of the stringers.

3. A one-sided separable fastener as defined in claim 2, wherein the scoops of one stringer include at their coupling end portions parts arranged and operating over the wear shelves of scoops of the companion stringer.

4. A one-sided separable fastener as defined in claim 1, wherein the scoops of both stringers are arranged in pairs, one scoop in each pair including the hook-shaped coupling member, and the other scoops of said pairs including the sockets for receiving the coupling members of companion stringers.

5. A one-sided separable fastener as defined in claim 4, wherein the pairs of scoops on one stringer include characterizations distinguishing the same from characterizations on the pairs of scoops on the companion stringer to denote left and right stringers.

6. A one-sided separable fastener as defined in claim 4, wherein the pairs of scoops on each stringer include wear shelves, over which coupling end portions of the scoops of opposed stringers are adapted to overlie when the stringers are coupled together.

7. A one-sided separable fastener as defined in claim 1, wherein the scoops of both stringers are arranged in pairs, the coupling end portions of the pairs of scoops on one stringer including the hook-shaped coupling members which are directed toward each other, the coupling end portions of the pair of scoops on the companion stringer having the hook-shaped coupling members extending in opposed directions to each other, and the scoops in both pairs including socket portions receiving the coupling members of the scoops of the opposed stringer.

8. A one-sided separable fastener as defined in claim 7, wherein the coupling end portions of the scoops on each stringer include wear shelves, upon which the coupling members of the scoops of opposed stringers move in coupling and uncoupling the stringers.

9. A one-sided separable fastener as defined in claim 8, wherein said wear shelves overlie at least part of the bead means of each stringer.

10. A one-sided separable fastener as defined in claim 1, wherein the hook-shaped coupling members are on the scoops of one stringer, the scoops of the companion stringer including sockets receiving the hook-shaped members of the scoops of the first stringer when said stringers are coupled.

11. A one-sided separable fastener as defined in claim 10, wherein the coupling end portions of the scoops on both stringers extend the full depth of the scoops, and outer portions of the coupling ends of both scoops include rounded portions for free passage of the scoops of one stringer over the tape of a companion stringer.

12. A one-sided separable fastener as defined in claim 11, wherein said rounded portions operatively engage the bead means of a companion stringer.
